DISCLAIMER.

DES. 71,347.—*Edward A. Zeh*, Passaic, N. J. A DISPLAY GLOBE. Patent dated October 26, 1926. Disclaimer filed June 11, 1927, by the patentee.

Hereby enters the following disclaimer, namely:

That he disclaims from the scope of the claim in U. S. Design Patent No. 71,347 of October 26, 1926, the design appearing upon the face of the globe illustrated in said patent, and consisting of a broken circle across the middle of which are two horizontal bars, and stipulates that said bar and circle design constitutes no portion whatever of said patented design, having been used merely for illustrative purposes to show the manner in which any such trade-mark design might be shown on globes of this kind.

UNITED STATES PATENT OFFICE.

EDWARD A. ZEH, OF PASSAIC, NEW JERSEY.

DESIGN FOR A DISPLAY GLOBE.

Application filed April 19, 1928. Serial No. 17,335. Term of patent 3½ years.

To all whom it may concern:

Be it known that I, EDWARD A. ZEH, a citizen of the United States of America, and a resident of Passaic, in the county of Passaic and State of New Jersey, have invented a new, original, and ornamental Design for Display Globe, of which the following is a specification, reference being had to the accompanying drawing, forming a part thereof.

In the drawing the figure represents a view in perspective of a display globe showing my new design.

I claim:

The ornamental design for a display globe as shown.

EDWARD A. ZEH.
